STEAM CABINET

Bernardo Ragone, Rosedale, N.Y., assignor to
T. J. Thomas Co., Inc., Brooklyn, N.Y.

Filed Oct. 2, 1967, Ser. No. 8,826

Term of patent 14 years

(Cl. D83—1)

FIG. 1.

FIG. 2.

FIG. 3.

FIG. 4.

FIG. 1 is a perspective view of a steam cabinet showing a front and side thereof;

FIG. 2 is an elevational view showing the right side thereof;

FIG. 3 is a top plan view thereof; and

FIG. 4 is an elevational view showing the left side thereof.

I claim:

The ornamental design for a steam cabinet, as shown.
